UNITED STATES PATENT OFFICE.

WILLIAM MASON, OF NEW HAVEN, CONNECTICUT, ASSIGNOR TO THE WINCHESTER REPEATING ARMS COMPANY, OF SAME PLACE.

MAGAZINE FIRE-ARM.

SPECIFICATION forming part of Letters Patent No. 295,081, dated March 11, 1884.

Application filed December 31, 1883. (No model.)

To all whom it may concern:

Be it known that I, WM. MASON, of New Haven, in the county of New Haven and State of Connecticut, have invented a new Improvement 5 in Magazine Fire-Arms; and I do hereby declare the following, when taken in connection with accompanying drawings and the letters of reference marked thereon, to be a full, clear, and exact description of the same, 10 and which said drawings constitute part of this specification, and represent, in—

Figure 1, a side view from the left, portions broken away to illustrate the engagement of the spring with the hub of the magazine-stop; 15 Fig. 2, a partial top view; Fig. 3, a longitudinal sectional side view; Fig. 4, the breech-piece and hammer detached, showing the arrangement of the trigger-piece with its sear and projection therefrom engaged, respectively, with the hammer and breech-piece; 20 Figs. 5 and 6, detached views to illustrate the operation of the cam upon the trigger-piece, whereby the hammer may be locked at full-cock and the breech-piece locked in its closed 25 position, or the breech-piece released, but so as to leave the sear engaged therewith in the full-cocked position; Fig. 7, a transverse section on line $x-x$ of Fig. 4; Fig. 8, the cam-lever which operates upon the trigger-piece, in 30 perspective, detached; Fig. 9, a side view, parts broken away to show the spring which acts upon the cam-lever; Fig. 10, a transverse section on line $y-y$, Fig. 9; Fig. 11, a view from the under side of the receiver, the trigger-guard plate removed; Fig. 12, the magazine check-lever, in perspective, detached; 35 Fig. 13, a front end view of the trigger-piece detached.

This invention relates to an improvement in 40 that class of magazine fire-arms in which a longitudinally-sliding bolt or breech-piece is arranged in the receiver and operated by means of a handle projecting at right angles from the breech-piece, secured in its closed 45 position by a shoulder on the breech-piece turned down forward of a shoulder on the receiver, and released from such closed position by turning the handle upward, so as to give a partial rotation to the breech-piece to bring

the locking-shoulder in line with a longitudinal slot in the receiver, such as are commonly called "bolt-guns," and in which a magazine is arranged in an inclined position in the butt-stock at the rear, opening into the receiver in a mouth inclined forward and upward, so that 50 the spring of the magazine will force the column of cartridges forward when the breech-piece is withdrawn, and so as to present the foremost cartridge into a position in front of the breech-piece, and so that the return or 55 closing of the breech-piece will force such presented cartridge into its place in the chamber in the rear end of the barrel, such magazine fire-arm being known as the "Hotchkiss Gun," the object being a simple cam and lever 60 mechanism, whereby the breech-piece may be locked in its closed position and the hammer in its cocked position, or both set free by one and the same cam, and also a simple check to hold the column of cartridges in the magazine 65 or permit them to be moved forward for use, as the case may be; and the invention consists in the construction of such locking devices, as more fully hereinafter described, and particularly recited in the claims. 70

A represents the receiver, to the forward end of which the barrel B is fixed. To the rear end the butt-stock C is applied, and forward the fore end is attached.

E is the breech-piece, arranged to slide longitudinally in the receiver, provided with a handle, F, by which it may be rotated, and so as to bring the shoulder G down in front of a corresponding shoulder, H, in the receiver, when the breech-piece is in its closed position, in substantially the usual manner for this class of arms. Centrally through the breech-piece the firing-pin I is arranged, provided at its rear end with a head, J, the head constructed with a shoulder, α , to engage the nose b of the sear, 80 all in substantially the usual manner. 85

K is the magazine, arranged in the stock at the rear, and opening beneath the breech-piece, also in the usual manner. The sear d is formed as a part of the trigger L. It is hung 90 above the magazine, as at e, but curved outward and inward, so as to pass outside the magazine and bring the trigger to a central 95

position below, as in the usual construction of this class of arms, and so that when the breech-piece has been opened for charging the arm, and the breech-piece then closed, the shoulder 5 *a* on the head of the hammer will engage the sear, leaving the hammer at full-cock and ready for discharge, as in the usual construction. The free end *f* of the spring *M* in the receiver bears upward on the trigger forward of the 10 pivot, the action of such spring being to bring the sear into the required engagement with the hammer. The notch or shoulder in the hammer is considerably deeper than is necessary for engagement with the sear, and so that 15 the nose end of the sear may be forced to a considerable extent beyond its natural engaged position into the recess forward of the shoulder, as seen in Fig. 4. Forward of the sear is an extension, *g*, and in the breech-piece is a 20 corresponding recess, *h*, the position of this recess being in line with the projection *g* when the breech-piece is in its closed position, with the handle turned down, and as seen in Fig. 2. When in this position, the projection *g* of the 25 trigger-piece may be forced up into the notch *h* in the breech-piece, as seen in Figs. 4, 5, and 7. If held in that condition, the trigger-piece will serve to lock the breech-piece in its closed position, and the trigger-piece, being there held, 30 also locks the hammer in its cocked position; but the projection of the nose *b* of the sear above the face of the extension *g* is greater than the depth of the notch in the breech-piece, and so that the trigger may be drawn back- 35 ward, so as to take the projection *g* from its notch in the breech-piece without bringing the nose of the sear so far down as to permit the hammer to escape, but will leave the hammer held by the trigger at the full-cocked position 40 and the trigger free to be pulled to release the hammer, in the usual manner.

To move the trigger as above described and lock it in position to hold the breech-piece in its closed position and the hammer in its 45 cocked position, I introduce a cam through the receiver—say on the right-hand side—the hub forming a bearing upon which the cam will readily turn, and on the outside provide this cam or hub with a handle, *N*, by which 50 the person manipulating the arm may turn the cam to its different positions. The cam is shown detached in Fig. 8. The hub *i* carries upon its inner face an eccentrically-placed cam-piece, *l*, which stands below a shoulder, 55 *m*, on the trigger-piece, and substantially above a second shoulder, *n*, on the trigger-piece, and so that the cam-piece *l* will work between the said two shoulders. In Figs. 5 and 6 this cam-piece is shown in its several 60 positions. In Fig. 6 the lever *N* is represented in broken lines in its horizontal position, and is also seen in Fig. 9, which is its normal position—that is, the position in which the parts of the arm are in condition for use. 65 The cam *l* rests upon the shoulder *n*, and serves as a stop to prevent the spring *M* from

throwing the trigger-piece beyond the proper cocked position when the sear is engaged with the hammer. Now, if from this position, Fig. 6, the lever be turned into the position seen 70 in Fig. 5, and as in broken lines, Fig. 9, the cam-piece *l* will pass under the shoulder *m* on the trigger-piece and force it upward, carrying the sear up onto the hammer-shoulder above the cocked position, and the projection 75 *g* on the trigger-piece into the notch *h* in the breech-piece, as seen in Fig. 5. This engagement of the trigger-piece with both the hammer-shoulder and the notch in the trigger-piece, and held by the cam-piece *l*, so as to 80 prevent the trigger from being pulled, will lock the breech-piece in its closed condition with the hammer at full-cock. Now, if it be desired to fire the gun, return the lever to the 85 position indicated in Fig. 6, which will bring the cam *l* onto the shoulder *n*, and turn the trigger-piece on its pivot down to the full-cock position, which movement will free the breech-piece from its lock and leave the hammer engaged with the sear as at full-cock, and 90 the hammer ready for use.

As the hub *i* on the lever *N* enters from the outside, and so that the lever remains upon the surface of the receiver, some device is necessary to not only hold the cam and its lever in their position for rotation, but also to locate the cam in either of the two positions to which it may be turned. I construct the hub *i* with a circumferential recess, *o*, and in the receiver I fix a spring, *P*, the nose of which 95 enters the recess *o*, as seen in Fig. 9. This spring lies close against the inside of the receiver, as seen in Fig. 11, and thus engages the hub when it is properly entered, and retains it in its seat. Transversely across the 100 recess *o* is a bar, *r*, and which rides over the end of the nose of the spring *P* as the hub is turned, and so that as the bar passes the nose of the spring the spring will be forced downward from the recess on one side of the bar, 105 and then will return and enter the recess upon the opposite side of the bar, and serve as a stop to hold the lever in either position to which it may be turned. The nose of the 110 spring falling into the recess either side of the bar indicates to the operator when the cam has been turned to its extreme position.

The spring *M* is constructed to form a dog, *R*, which will enter through an opening in the bottom of the magazine to stop the cartridge 115 next the foremost one when the breech-piece is opened, so as to check the column of cartridges and prevent other than the first from passing out through the mouth. This dog flies up, as seen in broken lines, when the trigger rises into its engagement with the notches in the hammer. Then when the trigger is pulled the dog is depressed and releases the column of cartridges, so that the one which is held back by the dog will pass 125 on beyond it, then, returning, will engage the next. This is a common and well-known de- 130

vice. An additional check, however, is desirable, not to say necessary, in this class of arms, whereby the entire column may be held in suspense for any required time, and the arm used simply as a breech-loader. To this end I apply a lever, S, similar to the lever N, but on the opposite side. This lever is shown detached in Fig. 12. It is provided with a hub, t, like the hub i on the lever N, and is constructed with a like circumferential recess, u, into which a spring, T, (seen in Figs. 1 and 11,) bears, the same as does the spring P into the recess in the hub of the lever N. On the hub is a stud, w, which projects inward, and so as to enter the top of the magazine through an opening, W. This stud is substantially concentric with the hub, but cut away upon one side, so as to leave a clear space through the magazine-tube when turned to the position seen in Fig. 3, and that position is the normal position for the lever S, as seen in Fig. 1. By turning the lever S upward to the position seen in broken lines, Fig. 1, the stud w is brought into the position seen in broken lines, Fig. 3, and so that it projects into the magazine so far as to engage the flange of the cartridge, as seen in broken lines, Fig. 3, and while the stud or stop w is thus turned the column of cartridges is held in reserve, and the arm may be used as a breech-loader. Then, when the cartridges in the magazine are required, return the lever S to its normal position, where it is engaged by the spring T and held.

As there is evidently no connection between the stop for the column of cartridges and the locking device for the hammer and breech-piece, and as both are of like construction so far as to their arrangement in the receiver and the device which holds them there, as well as retains them in the position to which they may be set, I do not wish to limit this construction of the hub and the arrangement of the spring whereby the stop or locking de-

vice is held in its seat to either the one or the other.

The locking device to engage the sear and a projection therefrom with both the hammer and the breech-piece may be applied in breech-loading arms which employ a like breech-piece and hammer, and is therefore not to be understood as limited to a magazine-arm.

I claim—

1. The combination of the longitudinally movable breech-piece and longitudinal hammer arranged through said breech-piece, a sear and projection therefrom constructed and arranged, respectively, so that the sear may engage a shoulder on the hammer and the said projection a corresponding notch in the breech-piece when the breech-piece is in its closed position, combined with a cam in connection with a lever on the outside of the receiver, substantially as described, whereby said sear and projection may be thrown into locking engagement with the breech-piece and hammer at full-cock or out of such locking engagement without releasing the hammer from its full-cock position.

2. The combination of a longitudinally movable breech-piece, a hammer arranged longitudinally through the breech-piece, the trigger-piece constructed with a sear, d, to engage a corresponding shoulder on the hammer, and with the projection g, to engage a corresponding notch in the breech-piece when the breech-piece is in its closed position, a cam, l, arranged through the side of the receiver, provided with a suitable handle upon its outside, the trigger-piece provided with shoulders m n, upon which the said cam will operate, substantially as described.

WILLIAM MASON.
